Primary Examiner—Bernard Ansher

[57] CLAIM

The ornamental design for a snow shovel handle, as shown and described.

DESCRIPTION

FIG. 1 is an isometric view of the snow shovel handle showing my new design;

FIG. 2 is a front elevation of the snow shovel handle;

FIG. 3 is a side elevation of the snow shovel handle; and FIG. 4 is a bottom plan view of the snow shovel handle.

FIG.1.

FIG.2.

FIG.3.

FIG.4.
